UNITED STATES PATENT OFFICE.

GEORGE BARRETT, OF VICTORIA, CANADA.

DESIGN FOR A BOARD.

SPECIFICATION forming part of Design No. 35,195, dated October 15, 1901.

Application filed August 17, 1901. Serial No. 72,452. Term of patent 14 years.

To all whom it may concern:

Be it known that I, GEORGE BARRETT, a subject of the King of Great Britain, and a resident of Victoria, in the Province of British Columbia and Dominion of Canada, have invented and produced a new and original Design for a Board, of which the following is a full, clear, and exact description.

The design relates to boards used as covering or weather-boards on frame houses.

Reference is to be had to the accompanying drawing, forming a part of this specification, in which the figure is a perspective view of a board, showing my design.

The design in its entirety consists of the body A, appearing at the lower front face with an ogee curve B, at the upper front corner with a longitudinal segmental groove C, and at the rear face, at the upper end, with a lon-

gitudinal groove D, approximately corresponding in shape to the lower edge B' of the body A.

The leading feature of the design consists of the body A, having the ogee curve B on one face at one edge and the groove D in its other face at its opposite edge.

Having thus fully described my invention, I claim as new and desire to secure by Letters Patent—

The design for a board, as herein shown and described.

In testimony whereof I have signed my name to this specification in the presence of two subscribing witnesses.

GEORGE BARRETT.

Witnesses:
